Primary Examiner — Wan Laymon*(74) Attorney, Agent, or Firm* — Frost Brown Todd LLC(57) **CLAIM**

The ornamental design for a linear surgical stapler, as shown and described.

DESCRIPTION

FIG. 1 is a perspective view of a linear surgical stapler, showing our new design;

FIG. 2 is a front elevational view of the linear surgical stapler of FIG. 1;

FIG. 3 is a rear elevational view of the linear surgical stapler of FIG. 1;

FIG. 4 is a left elevational view of the linear surgical stapler of FIG. 1;

FIG. 5 is a right elevational view of the linear surgical stapler of FIG. 1;

FIG. 6 is a top plan view of the linear surgical stapler of FIG. 1; and,

FIG. 7 is a bottom plan view of the linear surgical stapler of FIG. 1.

The broken lines in the FIGS. 1-7 are for the purpose of illustrating portions of the linear surgical stapler and form no part of the claimed design.
